UNITED STATES PATENT OFFICE.

CHARLES MABEL, OF FORT COLLINS, COLORADO; FRANCIS MABAL, ADMINISTRATRIX OF CHARLES MABEL, DECEASED, ASSIGNOR, BY DIRECT AND MESNE ASSIGNMENTS, TO JOHN A. C. KISOCK, OF SAME PLACE.

CARPET-STRETCHER.

SPECIFICATION forming part of Letters Patent No. 426,030, dated April 22, 1890.

Application filed June 22, 1889. Serial No. 315,167. (No model.)

To all whom it may concern:

Be it known that I, CHARLES MABEL, a citizen of the United States, residing at Fort Collins, in the county of Larimer and State of Colorado, have invented a new and useful Carpet-Stretcher, of which the following is a specification.

This invention relates to carpet-stretchers, and it has for its object to provide a device which shall be simple and inexpensive in construction and effective in operation.

The invention consists in the improved construction and arrangement of parts, which will be hereinafter fully described, and particularly pointed out in the claims.

In the drawings, Figure 1 is a perspective view of my improved carpet-stretcher. Fig. 2 is a longitudinal vertical sectional view of the same. Fig. 3 is a transverse sectional view. Fig. 4 is a detail view of the sliding head of my improved carpet-stretcher detached from the ratchet-bar.

The same letters refer to the same parts in all the figures.

A designates a ratchet-bar, of suitable length, provided at its front end with a vertical prong B, and provided at its lower edge with laterally-extending flanges C C, terminating at a short distance from the rear end of said ratchet-bar, where the ends of the said flanges form shoulders D.

The sliding head of my improved carpet-stretcher comprises a transverse bar E, provided with a series of prongs F on its under side, adapted to engage the carpet. The upper side of the bar E is provided with centrally-located upwardly-extending lugs G G, a suitable distance apart to admit of the passage of the ratchet-bar A, for the accommodation of the flanges C, of which recesses H are formed at the lower inner ends of the lugs G. Between the upper ends of said lugs is pivoted a pawl I, adapted to engage the ratchet-bar.

The transverse bar E of the head is provided with rearwardly-extending arms or brackets J J, the rear ends of which are journaled by a bearing-plate K, adapted to support the flanged lower edge of the ratchet-bar and pro-

vided with longitudinal flanges L, between which the flanges C of the said ratchet-bar will be guided. The arms or brackets J J are provided with lugs M, between which are pivoted the ends of the arms N of a bifurcated lever O, the outer end of which is provided with a suitable handle. A pawl P is connected pivotally to the under side of the lever O and adapted to engage the ratchet-bar A. The extreme end of said pawl B is provided with lugs Q Q, extending downwardly on either side of the ratchet-bar, in order to hold the said pawl in engagement with the latter and prevent it from being displaced laterally.

To the rear end of the ratchet-bar A, on the sides of the latter, are pivoted a pair of arms R R, between the outer ends of which is mounted a roller S, to admit of the carpet's sliding freely under the stretcher when the latter is in operation. It will be noticed that the arms carrying the said roller may be swung rearward to a horizontal position, so as not to interfere with the passage of the bearing-plate K of the sliding head, while at the same time the said arms perform the function of retaining the said sliding head upon the ratchet-bar.

The operation of my invention will be readily understood from the foregoing description, taken in connection with the drawings hereto annexed. The prong at the front end of the ratchet-bar is driven into the floor of the room adjacent to the base-board, the sliding head is then moved in a rearward direction upon the ratchet-bar and its teeth caused to engage with the carpet, which may then be stretched by operating the lever O in the usual manner, the pawl I serving to retain the sliding head in the position to which it is adjusted. The roller at the rear end of the device enables the carpet to slide freely under the same without catching against any of its parts.

Having thus described my invention, I claim—

1. In a carpet-stretcher, the combination of a ratchet-bar having a vertical prong at its front end and provided at its lower edge with laterally-extending flanges, a sliding head

comprising a transverse-bar having downwardly-extending prongs and provided with centrally-located upwardly-extending lugs, at the lower ends of which recesses are formed
5 to admit the flanged ratchet-bar, a pawl pivoted between the upper ends of said lugs, and brackets or arms extending rearward from said cross-bar and connected by a bearing-plate having longitudinal guide-flanges and a
10 bifurcated lever, the ends of the arms of which are connected pivotally to lugs upon the rearwardly-extending arms of the cross-bar of the sliding head, and having a pawl pivoted to its under side and engaging the
15 ratchet-bar, substantially as and for the purpose set forth.

2. In a carpet-stretcher, the combination of a ratchet-bar having a vertical prong at its front end and provided at its lower edge with
20 laterally-extending flanges terminating at a short distance from its rear end, the sliding

head having a transverse cross-bar provided with downwardly-extending prongs and provided with the pivoted pawl engaging the ratchet-bar, a lever connected pivotally to the 25 sliding head and having a pawl engaging the ratchet-bar and provided with lugs extending downwardly from each side of the latter, the arms connected pivotally to the rear end of the ratchet-bar in rear of the laterally-extending flanges of the latter, and a roller journaled between the outer ends of the said arms, substantially as and for the purpose herein set forth.

In testimony that I claim the foregoing as 35 my own I have hereto affixed my signature in presence of two witnesses.

CHARLES MABEL.
